UNITED STATES PATENT OFFICE.

WINFIELD SCOTT ARTHUR, OF WOODSTOWN, NEW JERSEY, ASSIGNOR OF ONE-HALF
TO SIPRON C. KEITH, OF WOODSTOWN, NEW JERSEY.

COMPRESSION-BIB.

1,017,492.

Specification of Letters Patent.

Patented Feb. 13, 1912.

Application filed July 5, 1910. Serial No. 570,473.

To all whom it may concern:

Be it known that I, WINFIELD SCOTT ARTHUR, a citizen of the United States, residing at Woodstown, in the county of Salem 5 and State of New Jersey, have invented new and useful Improvements in Compression-Bibs, of which the following is a specification.

This invention relates to certain new and 10 useful improvements in valves or faucets, such as are adapted for controlling the flow of fluid through passages; and the primary object of the invention is to provide a device of this character with auxiliary means 15 for controlling the flow of fluid independently of the control exercised through the medium of the main valve, so that the escape of fluid past the main valve is prevented when the said main valve is removed 20 for repairs.

With the above, and other objects in view, which will appear as the description progresses, the invention resides in the novel construction and combination of parts here- 25 inafter fully described and claimed.

In the accompanying drawings there has been illustrated a simple and preferred embodiment of the improvement, and in which drawings,

30 Figure 1 is a central longitudinal sectional view taken through my improved bib or faucet showing the main valve seated. Fig. 2 is a similar view showing the main valve unseated for the passage of fluid 35 through the bib or faucet. Fig. 3 is a similar view showing the auxiliary valve seated and the main valve in a position to be removed for repairs.

With the ordinary construction of bibs 40 or faucets the operating stem is provided with a fiber washer which serves as a valve. It is not infrequent that these valves become worn and rendered useless for preventing the flow of water, and in order to 45 repair the said valve the stem containing the valve must be removed from the faucet. In order to accomplish this without preventing the flow of the water through the outlet spout or nipple of the faucet, it is 50 necessary to turn off the cock which controls the entrance of water to the house. This cock is almost invariably positioned adjacent the point where the inlet pipe enters the house, and this point is frequently in the basement or cellar and at

quite a distance away from the bath or other room in which the bib is positioned. The controlling cock is provided with a drip opening, and all of the water contained within the pipe system of the house will 60 drain through this opening when the cock is turned off, thus flooding the floor as well as adding to the inconvenience of the person repairing the bib. Should the valve become disarranged in the night or in some 65 other period when a plumber is not at hand the water must be entirely turned off in the house or the same allowed to freely flow through the bib, which is a source of irritation and worry to the occupants 70 as well as an expensive addition to the water rent.

It is the primary object of the present invention to overcome these difficulties by providing a faucet or bib with a pair of 75 valves, one arranged above the other, so that, should one of the valves become worn the second valve will be readily brought into use, and furthermore to provide means whereby the main operating valve and its 80 stem may be disconnected for repairing without the necessity of the employment of the inlet controlling cock.

In the accompanying drawings the numeral 1 designates a bib or faucet connected 85 in accordance with the present invention. This bib 1 comprises an inlet pipe 2 and an outlet spout 3, the said pipes or spouts being divided from each other through the medium of partitions 4 and 5. These partitions 4 and 5 are intermediately connected 90 to provide a communicating opening between the said members 2 and 3 as well as to provide an upper valve seat 6 and a lower valve seat 7. Positioned directly 95 above the valve seat 6, and integrally formed with the pipes or spouts 2 and 3 is a boss or extension 8. This extension 8 is hollow and is provided for practically its entire length with interior threads 9 and has its 100 upper portion provided with exterior threads 10.

The numeral 11 designates a cap which is adapted to engage the exterior threads 10, and positioned between the under face 105 of the cap and the top of the base 8 is a washer 12. The cap 11 is provided with a reduced upwardly projecting portion 14 the same being provided with exterior threads, and these exterior threads are adapted to be 110

engaged by interior threads formed upon an auxiliary cap 15. The extending portion 14 of the cap 11 is provided with a central bore, and the head of the auxiliary cap 15 is provided with an alining opening, and positioned between the auxiliary cap 15 and the top of the extension of the cap 11 is a suitable packing 16.

The numeral 17 designates the handle 10 stem and 18 the handle connected therewith. The lower portion of the stem 17 is provided with a threaded head 18', the same being adapted to engage with the threads 9 provided upon the boss 8. The 15 head 18' is centrally provided adjacent its lower face with a threaded bore 19, and adapted to be engaged within the said bore is the threaded portion 20 of what I term a valve securing stem 21. This stem 21 is 20 centrally provided with an enlarged head 22 and extending downwardly from the said head is a pin or finger 23 which is positioned directly in a line with the threaded extension 19 of the said stem. Positioned 25 between the head 18' of the stem 17 and the enlargement 22 of the valve securing stem 21 is a fibrous valve 24, the latter being adapted to engage the upper valve seat 6 provided by the partitions 4 and 5 when the 30 handle 18 is rotated so as to force the threaded head 18' toward the said seat.

The bib or faucet is provided with a downwardly extending nipple 25 which is arranged directly below the valve seat, and 35 the said nipple is provided with interior threads, the same being adapted to engage with exterior threads 26 provided upon the cap screw 27. This cap screw 27 is provided with an annular offset 28, the latter being of a non-circular formation so as to readily adapt itself for the reception of a wrench or other removing element. Positioned 40 within the cap screw 27 is the auxiliary valve 29. This valve 29 comprises a beveled or inclined portion 30 forming the valve proper, a projecting guide tube 31 extending upwardly from the said valve 30 and a depending casing 32. Positioned 45 within this casing 32 is a helical spring 33, the latter adapted to exert pressure between the cap screw and the said valve 29 so as to force the valve upwardly and into engagement with the valve seat 7. The guide tube 31 is adapted to engage the projecting portion 33 of the valve retaining stem 21, and the interior of the screw cap 27 approximately equals that of the cylinder 32 of the valve seat, so that it will be noted that the 50 said valve 29 may be effectively guided 55 against its seat when the head 18' is in the position illustrated in Fig. 3 of the draw-

ings. Positioned between an offset or shoulder on the cap screw 27 and the nipple 25 is a washer 34 so as to render a water-tight joint between the said nipple and cap screw. 65

The extremity of the curved outlet pipe or spout of the bib or faucet is provided with exterior threads 35 and directly above the said threads is an offset or shoulder 36.

The numeral 37 designates the discharge 70 nozzle for the outlet spout. This nozzle is of a substantially frusto-conical formation, having its upper or enlarged portion provided with interior threads 38 which are adapted to engage the threads 35. Positioned 75 between the shoulder 36 and the upper portion of the discharge nozzle 37 is a washer 39, and the said discharge nozzle is provided with an annular shoulder 40 directly below its threaded portion 38. Resting 80 upon this shoulder, and contacting the lower extremity of the outlet spout 3 is a strainer 41, the latter being adapted to catch all animal life passing through the water. 85

From the above description, taken in connection with the accompanying drawings, it will be noted that I have provided an extremely simple and effective device for the purpose intended, and while I have illustrated and described the preferred embodiment of the improvement, as it now appears to me, minor details of construction, within the scope of the following claim may be resorted to if desired. 90

Having thus fully described the invention, what I claim as new is:—

A faucet of the class described, comprising inlet and outlet members, a partition intermediate the members and having an 100 opening formed therein, valve seats formed at the top and bottom of said opening, a main valve including a head, adapted to engage the upper seat, a fibrous washer, a member threaded in said head and formed 105 with an enlarged portion intermediate its ends, the said enlarged portion forming a clamp to secure the washer to the head, a pin depending from said enlarged portion, a spring pressed valve located below the 110 partition and adapted to be seated upon the lower side thereof, a guide tube projecting upwardly from said valve and formed integral therewith, and said guide tube being adapted to receive the said pin whereby 115 to hold the valve and plug in alinement.

In testimony whereof I affix my signature in presence of two witnesses.

WINFIELD SCOTT ARTHUR.
